FIG. 3.

Charles H. Coons
F. W. Bell and Keagin
, his Attorneys

Patented Apr. 7, 1925.

UNITED STATES PATENT OFFICE.

CHARLES H. COONS, OF SAUGERTIES, NEW YORK, ASSIGNOR OF THREE-FIFTHS TO THE
TISSUE COMPANY, OF SAUGERTIES, NEW YORK, A CORPORATION OF NEW YORK.

NAPKIN-FOLDING MACHINE.

Application filed January 19, 1922. Serial No. 530,288.

To all whom it may concern:

Be it known that I, CHARLES H. COONS, of Saugerties, in the county of Ulster and State of New York, have invented certain new and useful Improvements in Napkin-Folding Machines; and I do hereby declare the following to be a full, clear, and exact description of the invention, such as will enable others skilled in the art to which it appertains to make and use the same.

This invention relates to paper folding machines, and more particularly to such machines as are designed for folding paper napkins. Paper napkins are now extensively used and there is large demand for such articles ready folded so that they may be placed in containers or arranged in neat piles, and the requirements of the trade as to size are varied. In consequence the manufacturer must either state his inability to supply a size other than that which may be produced by his machines or he must have a number of machines each capable of turning out a different size of folded napkins which means a slowing down of production unless he has orders which will keep each of his machines going. It is the object of my invention to provide an improved and simple machine which may be used for folding different sizes of napkins, thus insuring against idleness of any machine because of lack of orders for articles of the size for which the machine may be adapted and providing for use of all machines to full working capacity with consequent speed of production. It is a requirement in successfully operating napkin folding machines where interfolding is not desired that each napkin to be folded be cut and moved for delivery from the machine without interference by the next succeeding napkin, and I have devised new and improved mechanism whereby the cooperating elements may be adjusted to effect proper synchronism for all sizes of napkins which the machine may handle.

In the drawings, Figure 1 is a view in side elevation of a napkin folding machine embodying my improvements. Figure 2 is a top plan view. Figure 3 is a diagrammatic view showing the draw rollers, the creasing rollers, and associated guide tapes. Appropriately supported by a bracket 1 upon a standard 2 is a folding horn 3, a

roller 4, likewise supported by the bracket, lying adjacent the horn and forming the lead thereto for a web of paper to be folded and cut into napkin lengths. A second roller 5 arranged transversely of the roller 4 is positioned at the small end of the horn and is the lead for the web which has been folded lengthwise over the horn, a pair of rollers 6 and 7 forming the means for drawing the paper over the roller 4, horn 3 and roller 5, it being understood that the web of paper is supported in the usual manner at the side of the machine. The two rollers 6, 7 are mounted on a frame 8 vertically movable in a housing 9 superposed on the standard 2, rails 10 at each side of the housing forming the guiding means for the up and down movement of the frame 8. This frame is raised and lowered through the instrumentality of rods 12 secured thereto at opposite sides and each having its upper end screw threaded for engagement of a gear nut 13, connected with worm gears 14 on a rod 15 operated by a hand wheel 16 at one side of the housing.

Power is appropriately communicated to a shaft 22 on one end of which is a gear 23, the shaft being appropriately blocked on the movable frame 8. Gear 23 is in mesh with an idler 24 adjustably mounted on an arm 25 which is itself movable into various positions, swinging from its pivot which is the shaft 26 upon which the roller 6 is mounted. This idler 24 meshes with gear 27 fast on the shaft 26 and drives the roller 6, a gear 27' on the opposite end of the shaft transmitting power to the gear 28 of the roller 7. The stub shaft 29 for the idler 24 is adjustable within a straightway slot 30 of the arm 25, and the position of the arm is regulated by a nutted bolt 31 projecting from an upright ear 32 of the movable frame 8, the bolt extending through an arcual slot 33 of the arm. Adjustment of position of the arm and of the idler thereon is required whenever the gear 23 is changed for a gear of another size as will be hereinafter explained.

In fixed relation to the shaft 22, and rotating therewith is a knife 36 which co-acts with a bed knife 37 mounted on the frame 8, the folded web being cut into appropriate napkin lengths by these blades.

Two rollers, 40, 41, arranged in the same vertical plane and supported by the standard 2, in complement, form creasing means for imparting the final transverse crease to the napkin which has been given an initial lengthwise fold as it passes over the horn 3. The roller 40 is driven by sprocket chain 40' from a sprocket on the shaft of roller 7, the chain travelling over a take-up roller 40''. These rollers 40 and 41 are in gear and are driven at a speed about one-third faster than the rotation of the rollers 6 and 7 so as to insure discharge of the napkin onto a layboy or other receiving means sufficiently in advance of the next oncoming napkin to prevent the latter overtaking the former. A folding blade 42 carried by a reciprocating cross head 43 tucks the severed napkin into the bite of the rollers 40, 41, this blade being actuated by an eccentric rod 44, the crank 45 being fixed to a sprocket driven shaft 46.

Endless bands or tapes are used for guiding the paper in its passage through the machine and such tapes are indicated at S, V, W, X, Y, and Z. These tapes are arranged about guiding rollers in a manner well known in the art, tapes which are cooperating being so spaced across the rollers as to not contact with complementary tapes. The tape S extends from the roller 6 to a guiding drum 6', and tape V, complementary to the tape S, extends from the roller 7 to a guiding drum 7'. Tape W is guided in its flight by drum 47 which is journaled between said plates of the movable frame 8, the upper roller 40 of the creasing means, a drum 48 supported by links 49, a drum 50 movable in a slideway 51 (a weight 51' acting to tension the tape), the lower roller 41 of the creasing means, and a drum 52 supported by the standard 2. Tape X which co-acts with tape W is guided by the lower roller 41, and drum 54. Tape Y extends between drums 55 and 56, the former being positively driven through gear connection with the shaft of roller 41. Acting in complement to the tape Y is a tape Z, an upper drum 57 journaled between side plates of the movable frame 8, two lower drums 58, 59 and an intermediate movable drum 60 forming the guiding elements for the tape Z, the drum 58 receiving motion from the drum 56, through a gear on each. The drum 60 is journaled in blocks 61 which are slidable in ways 62 of a bracket 63 secured to the standard 2, a weight 64 connected with the blocks 61 tensioning the tape.

In the operation of my device for a given size of napkin, a web of crêpe paper suitably supported at the side of the machine is fed over the roller 4 down onto the folding horn 3 from which it is drawn by the rollers 6 and 7, being fed by these rollers between the complementary tapes S and V down to

and past the bed knife 37, the advancing length being then gripped between the tape Z and the tape W, and then immediately further on between the tape Z and the tape Y. The advancing edge is carried along 70 by the tapes Z and Y, and immediately the rotating knife co-acting with the bed knife severs the length, folding blade 42 engages the now severed length and tucks it in between the creasing rollers 40 and 41, the tapes W and X guiding the napkin through these rollers and down to a point where they are received on a delivery table 70 and packed by a stacker 71 on the end of an arm 72 connected with a reciprocating cross 80 head 73 operated by an eccentric rod 74 appropriately connected with a sprocket driven shaft 75. It will be noted that as the napkin is engaged by the tucker blade the lower end thereof is being pulled against pressure 85 exerted by the tapes Z and Y, consequently there must not be too great a friction exerted by these tapes but only sufficient to insure the carrying of the advancing edge of a napkin down past the point of entrance 90 between the creasing rollers.

In adjusting the machine for the purpose of producing a napkin of a different size it is first necessary to remove the gear 23 and to substitute therefor a larger or 95 a smaller gear, the idler gear 24 being then adjusted on its arm 25 so as to compensate for the difference in size of the gear 23 rotation being communicated from the gear 23 to the gear 27 through this idler. It is also necessary to lengthen or shorten the 100 distance between the bed knife 37 and the plane of movement of the folding blade 42, it being understood that the blade is intended to strike the severed sheet about midway 105 its length so as to give it the correct fold. Accordingly it is required that the frame 8 shall be moved up or down, carrying with it the drawing rollers 6 and 7, the bed knife 37 and its complementary knife 36 which is mounted on the shaft 22, with all related 110 parts. This movement of the frame is accomplished by turning the hand wheel 16, the power thus communicated being transferred through the rod 15 and worm gears 115 14 thereon to the gear nuts 13 on each of the rods 12 which are connected at the sides of the frame 8. As will be apparent, in the movement of the frame and the parts carried thereby it is necessary that the sprocket chain 80 which effects the drive of the shafts with which the eccentric rods 44 and 74 are connected shall always be maintained taut. To insure this I provide a sliding block 81 which may be adjusted on the frame 2, the block forming a bearing for an idler sprocket 83. The position of the parts in Figure 1 indicates the arrangement for folding the smallest size of napkin, the cutting blades being in their lowermost po- 120 125 130

sition. The gear 23 having been changed and the idler 24 adjusted to the change in size of such gear 23, to effect a difference in the speed at which the drawing rollers are

- 5 driven, turning of the hand wheel 16 to the right will effect a clockwise turning of the nut 13 and consequent lifting of the frame 8 to the desired position. Before this lifting may be accomplished it is necessary to 10 loosen the sliding block 81 to permit the chain 80 to rise with the frame and to loosen the take up roller 40" to permit adjustment of the chain drive between rollers 7 and 40. The upward movement of the 15 frame will also alter the position of the chain 40' and each of the tapes W and Z, the means permitting this change of these elements having been heretofore described.

I claim as my invention:

- 20 1. In a napkin folding machine, means for initially folding a web of paper, a pair of drawing rollers, cooperating cutting means for severing the folded paper, guiding means for such severed sheet, means for 25 transversely folding such sheet arranged in spaced relation to said cutting means, and means for varying the distance between said cutting means and said last named folding means.
2. In a napkin folding machine, means for initially folding a web of paper, a pair of drawing rollers, cooperating cutting means for severing the folded paper, tapes for guiding such severed sheet, means for trans- 35 versely folding such sheet including a folding blade and a pair of rollers arranged in spaced relation to said cutting means, and means for varying the distance between said cutting means and said last named folding means.
3. In a napkin folding machine, means for initially folding a web of paper, a pair of drawing rollers, cooperating cutting means for severing the folded paper, guiding means 40 for such severed sheet, means for effecting a transverse fold of such sheet and its feed toward delivery from the machine at a speed greater than the speed at which such severed sheet is presented to the transverse folding 45 means, the latter means being arranged in spaced relation to said cutting means, and means for varying the distance between the transverse folding means and the cutting means.
5. In a napkin folding machine, means for initially folding a web of paper, a pair of drawing rollers, cooperating cutting means including a fixed cutting blade and a rotary blade for severing the folded paper, guiding 60 means for such severed sheet, a reciprocating folding blade and a pair of rollers cooperating to transversely fold such sheet and feed it toward delivery from the machine at a speed greater than the speed at which such 65 severed sheet is presented to the folding

blade and cooperating rollers, said blade and rollers being arranged in spaced relation to said cutting means, and means for varying the distance between said blade and rollers and said cutting means.

5. In a napkin folding machine, a standard, means for initially folding a web of paper, a housing superposed on said standard, a frame movable in said housing, a pair of drawing rollers, a co-acting cutting means 75 carried by said frame, means for transversely folding the initially folded sheet, said means being arranged in spaced relation to said cutting means, and means for moving said frame to vary the distance between 80 said cutting means and said last named folding means.

6. In a napkin folding machine, a standard, means for initially folding a web of paper, a housing superposed on said standard, a frame movable in said housing, a pair of drawing rollers, a co-acting cutting means carried by said frame, means mounted on said standard for transversely folding the initially folded sheet, such means being in 90 spaced relation to said cutting means, and means for moving said frame to vary the distance between said cutting means and said last named folding means.

7. In a napkin folding machine, a standard, means for initially folding a web of paper, a housing superposed on said standard, a frame movable in said housing, a pair of drawing rollers, a co-acting cutting means carried by said frame, a folding blade 105 mounted for reciprocal movement in said standard, a pair of rollers mounted in said standard and adapted to cooperate with said blade to transversely fold such sheet and feed it toward delivery from the machine at a speed greater than the speed at which such severed sheet is presented to the folding blade and cooperating rollers, such blade and rollers being in spaced relation to said cutting means, and means for moving said frame to vary the distance between 110 said cutting means and said blade and rollers.

8. In a napkin folding machine, a standard, means for initially folding a web of 115 paper, a housing superposed on said standard, a frame movable in said housing, a pair of drawing rollers mounted on said frame, a driven member carried by said frame, cutting means in part carried by said driven member and in part mounted on said frame for severing the folded paper in predetermined lengths, gearing for transmitting power from said driven member to said rollers, means whereby said gearing may be 120 changed to vary the speed of said drawing rollers, means for transversely folding such severed sheet, such means being in spaced relation to said cutting means, and means for raising and lowering said frame to vary 125

the distance between said cutting means and said transverse folding means.

9. In a napkin folding machine, a standard, means for initially folding a web of paper, a housing superposed on said standard, a frame movable in said housing, a pair of drawing rollers mounted on said frame, a driven member carried by said frame, cutting means in part carried by said driven member and in part mounted on said frame for severing the folded paper in predetermined lengths, gearing for transmitting power from said driven member to said rollers including a gear wheel on said driven member, an adjustably mounted idler, and cooperating gear wheels on said rollers, said adjustably mounted idler permitting change of the ratio of said gearing to vary the speed of said draw rollers, means for transversely folding such severed sheet, such means being in spaced relation to said cutting means, and means for raising and lowering said frame to vary the distance between said cutting means and said transverse folding means.

10. In a napkin folding machine, a standard, means for initially folding a web of paper, a housing superposed on said standard, a frame movable in said housing, a pair of drawing rollers mounted on said frame, a driven member carried by said frame, cutting means in part carried by said driven member and in part mounted on said frame for severing the folded paper in predetermined lengths, gearing for transmitting power from said driven member to said rollers including a gear wheel on said driven member, an adjustably mounted idler, and cooperating gear wheels on said rollers, said adjustably mounted idler permitting change of the ratio of said gearing to vary the speed of said draw rollers, a pair of rollers mounted in said standard and adapted to cooperate with said blade to transversely fold such sheet, said blade and said rollers being in spaced relation to said cutting means, driving connections between said driven member, said blade and said last named rollers whereby said blade and rollers act to fold and to feed such sheet toward delivery from the machine at a speed greater than the speed at which said sheet is fed to position for said transverse folding, and means for raising and lowering said frame to vary the distance between said cutting means and said blade and rollers.

11. In a napkin folding machine, a standard, means for initially folding a web of paper, a housing superposed on said standard, a frame movable in said housing, a pair of drawing rollers mounted on said frame, a driven member carried by said

frame, cutting means in part carried by said driven member and in part mounted on said frame for severing the folded paper in predetermined lengths, gearing for transmitting power from said driven member to said rollers including a gear wheel on said driven member, an adjustably mounted idler, and cooperating gear wheels on said rollers, said adjustably mounted idler permitting change of the ratio of said gearing to vary the speed of said draw rollers, a folding blade mounted for reciprocal movement in said standard, a pair of rollers mounted in said standard and adapted to cooperate with said blade to transversely fold such sheet, said blade and said rollers being in spaced relation to said cutting means, a plurality of guiding tapes for feeding such sheet into position to be acted on by said folding blade and cooperating rollers, means for raising and lowering said frame to vary the distance between said cutting means and said transverse folding blade and rollers, and means permitting variation in length of the guiding portions of some of said guiding tapes.

12. In a napkin folding machine, a standard, means for initially folding a web of paper, a housing superposed on said standard, a frame movable in said housing, a pair of drawing rollers mounted on said frame, an arm pivotally supported by the shaft of one of said rollers, said arm having an arcual slot and a straightway slot, an upright ear on said frame to which said arm is bolted through said arcual slot, a driven member carried by said frame, cutting means in part carried by said driven member and in part mounted on said frame for severing the folded paper in predetermined lengths, gearing for transmitting power from said driven member to said rollers including a gear wheel on said driven member, an idler on said arm and adjustable within the straightway slot thereof, and cooperating gear wheels on said rollers, said adjustably mounted idler permitting change of said gearing to vary the speed of said draw rollers, means for transversely folding such severed sheet, such means being in spaced relation to said guiding means, and means for raising and lowering said frame to vary the distance between said cutting means and said transverse folding means.

13. In a napkin folding machine, a standard, means for initially folding a web of paper, a housing superposed on said standard, a frame movable in said housing, and having upwardly extending screw threaded rods, a pair of drawing rollers mounted on said frame, an arm pivotally supported by the shaft of one of said rollers, said arm having an arcual slot and a straightway slot, an upright ear on said frame to which said arm is bolted through

said arcual slot, a driven member carried by said frame, cutting means in part carried by said driven member and in part mounted on said frame for severing the 5 folded paper in predetermined lengths, gearing for transmitting power from said driven member to said rollers including a gear wheel on said driven member, an idler on said arm and adjustable within the 10 straightway slot thereof, and cooperating gear wheels on said rollers, said adjustably mounted idler permitting change of said gearing to vary the speed of said draw rollers, means for transversely folding such 15 severed sheet, such means being in spaced relation to said guiding means, worm nuts engaging said screw threaded rods and manually operable worms for engaging said 20 worm nuts to effect a raising and lowering of said frame to vary the distance between said cutting means and said transverse folding means, and means for raising and lowering said frame to vary the distance between 25 said cutting means and said transverse folding means.

14. A napkin folding machine including means for initially folding a web of paper, a movable frame, drawing rollers for the folded web carried by said frame, cutting 30 means for severing the folded paper mounted in said frame, means for transversely folding the severed sheet, means for moving the frame to adjust the cutting means relative to the last mentioned folding 35 means, and means for varying the speed of the drawing rollers relative to the adjustment of said frame.

15. A napkin folding machine including means for initially folding a web of paper, 40 a movable frame, drawing rollers for the folded web carried by said frame, rotatable cutting means mounted in the frame, driving means for the cutting means, a driving connection between the cutting means and the drawing rollers, means for transversely 45 folding the severed sheet, means for moving the frame for adjusting the relation of the cutting means with the last mentioned folding means, and means for changing the 50 driving relation of the cutting means with the drawing rollers to vary the feed of the folded sheet with respect to the cutting means.

16. A napkin folding machine including 55 means for initially folding a web of paper, a movable frame, drawing rollers for the folded web carried by said frame, rotatable cutting means mounted in the frame, driving means for the cutting means, a driving 60 connection between the cutting means and the drawing rollers adapted for adjustment to change the relative speed of the rollers and cutting means, means for transversely folding the severed sheet, means for moving 65 the frame to adjust the relation of the cut-

ting means with the last mentioned folding means, and an adjustable driving connection between said cutting means and the last mentioned folding means for operating said folding means. 70

17. A napkin folding machine including means for initially folding a web of paper, a movable frame, drawing rollers mounted therein for feeding the folded web through the machine, rotatable cutting means 75 mounted on the frame for severing the folded web, means for driving the cutting means, a driving connection between the cutting means and the drawing rollers adapted for adjustment to vary the speed 80 relation between the cutting means and drawing rollers, a transverse folding means for folding the severed sheet, reciprocating stacking means for receiving and stacking the folded sheets, means for adjusting the 85 frame relative to the last mentioned folding means, and an adjustable driving connection between the cutting means and the last mentioned folding and stacking means for driving said members at a relatively fixed 90 speed.

18. In a napkin folding machine, means for initially folding a web of paper, a pair of drawing rollers, cooperating cutting 95 means for severing the folded paper, guiding means for such severed sheet, means for transversely folding such sheet, said cutting means being arranged in spaced superposed relation thereto, and means for varying the 100 distance between said cutting means and said last named folding means.

19. In a napkin folding machine, means for initially folding a web of paper, a pair of drawing rollers, cooperating cutting means for severing the folded paper, tapes 105 for guiding such severed sheet, means for transversely folding such sheet including a folding blade and a pair of rollers, said cutting means being arranged in spaced superposed relation to said last named folding 110 means, and means for varying the distance between said cutting means and said last named folding means.

20. In a napkin folding machine, means for initially folding a web of paper, a pair 115 of drawing rollers, cooperating cutting means for severing the folded paper into predetermined lengths, guiding means for such severed sheet, means for transversely folding such sheet arranged in spaced relation to said cutting means, and means for varying the distance between said cutting means and said last named folding means whereby the latter may be positioned midway and at other points between the ends 120 of the severed sheet.

21. In a napkin folding machine, means for initially folding a web of paper, a pair of drawing rollers, cooperating cutting 125 means for severing the folded paper into 130

predetermined lengths, tapes for guiding such severed sheet, means for transversely folding such severed sheet including a folding blade and a pair of rollers arranged in spaced relation to said cutting means, and means for varying the distance between said cutting means and said last named folding

means whereby to permit said folding blade to act upon severed sheets of varying lengths midway and at other points between its ends. 10

In testimony whereof I have signed this specification.

CHARLES H. COONS.
